J. H. NOLD,
MEANS FOR CRATING PLASTER BOARD AND THE LIKE.
APPLICATION FILED JAN. 22, 1919.

UNITED STATES PATENT OFFICE.

JOHN H. NOLD, OF CHICAGO, ILLINOIS, ASSIGNOR TO UNITED STATES GYPSUM COMPANY, OF CHICAGO, ILLINOIS, A CORPORATION OF NEW JERSEY.

MEANS FOR CRATING PLASTER-BOARD AND THE LIKE.

1,354,509.

Specification of Letters Patent.

Patented Oct. 5, 1920.

Application filed January 22, 1919. Serial No. 272,543.

To all whom it may concern:

Be it known that I, JOHN H. NOLD, a citizen of the United States, residing at Chicago, in the county of Cook and State 5 of Illinois, have invented certain new and useful Improvements in Means for Crating Plaster-Board and the like, of which the following is a description.

In the handling and transportation of 10 such materials as plaster board, constructed of gypsum or analogous material, it has been found necessary to crate the board in order to protect it from accidental injury. The custom usually employed has been to 15 place a number of said sheets or boards one upon the other with the edges substantially in registry with one another, and practically box the edges in. That is, a strip is employed extending around the edges and 20 covering the same, and then upon each flat surface of the board strips are placed which are secured to the edge strips mentioned. This is a comparatively expensive method, using an unnecessary quantity of material, 25 which is expensive, and taking considerable time to properly crate the board. My invention has for its object to simplify the method of crating board, resulting in substantial economy in both time and material, 30 and accomplishing the desired object in a thoroughly satisfactory manner. To this end my invention consists in the novel method of and means for crating such sheets of material.

35 In the drawings, wherein like indicating characters indicate like or corresponding parts,

Figure 1 is a perspective view of a plurality of sheets of plaster board crated ready for transportation or handling by my improved method;

Fig. 2 is a transverse section on the line 2—2 of Fig. 1;

Fig. 3 is a section substantially on the line 3—3 of Fig. 1; and

Fig. 4 is a section similar to Fig. 3 illustrating further improved means for this purpose.

In the drawings, 1 indicates the top board 50 of three sheets of plaster board placed one upon the other with the edges substantially in registry with one another. 2 are strips of suitable material upon which the piled boards are placed in such a manner that the 55 strip 2 projects beyond the side edges 3 of

the board to protect the same. A strip of this material is placed on two edges, preferably extending the longer way of the piled boards so that as the boards are placed on edge they may be pushed along the floor 60 or surface without the edges touching, and without the end strips being accidentally torn off. Directly above the strips 2, resting upon the upper surface of the board 1, are mating strips 4—4, likewise extending 65 slightly beyond the edges of the board. These two strips 2 and 4 are secured together and to the board in any desired manner, preferably by ordinary nails 5 driven through the strips 4 and the intervening 70 sheets of plaster board into the strips 2. The nails are preferably well set down so that the heads will not project to interfere or catch when the crates are piled one upon another. The nails are preferably only of 75 such length as to extend securely into the strips 2, and not extend farther. I prefer to employ this method rather than permit the nails to extend through and clench the same, as some difficulty may be met in re- 80 moving the nails and uncrating the board. At the ends of the crated boards, extending between the strips 2, are similar strips 6, preferably also extending beyond the edges of the board, as stated, while upon the upper 85 surface of the board are strips 7—7 mating the strips 6, and in both cases preferably extending between the side strips for the reason stated.

In the form shown in Fig. 4, the strips 6 90 and 7, as shown, are provided with offset portions 8 which extend over and partially cover the edges of the board. This construction insures the proper projection of the protecting strips beyond the edge of the board, 95 and gives an increased sliding surface when the crate is pushed along the floor. The projections 8 may be only sufficient to insure the accurate spacing of the strips beyond the edge of the board, or if preferred, they may 100 be longer and serve to substantially cover the edges of the board. In any event, however, I prefer that the approximate extensions 8 shall not come in contact when the crate is completed, thus insuring the strips 105 6 and 7 firmly and reliably resting upon the flat surface of the boards to which they are firmly secured by the attaching of the securing elements 5.

In practice I have found it preferable to 110

use a heavier strip for one of the protecting strips, for illustration, the strips 2 and 6, and such material as will firmly hold a nail. I have secured very satisfactory results with 5 what is termed "hard wood" strips for this purpose. I also prefer to employ strips of what is termed "soft wood" for the strips 4 and 7, as the nail readily passes through them, and the head of the nail readily sets 10 down into or below the surface of the strip so as not to catch when the crates are piled one upon another. Any preferred tool or implement for withdrawing nails may be effectively employed in removing the nails 15 and releasing the boards from the crate.

While I prefer to secure and crate a plurality of sheets as stated, for strength of and economy in crating, it is obvious that single sheets may be so crated with equally 20 satisfactory results, so far as security is concerned.

Having thus described my invention, it is 25 obvious that various immaterial modifications may be made in the same without departing from the spirit of my invention; hence I do not wish to be understood as limiting myself to the exact form, construction, arrangement and combination of parts herein shown and described, or uses mentioned.

30 What I claim as new and desire to secure by Letters Patent is:

1. A crate of plaster board, comprising one or more sheets of plaster board provided with suitable material arranged on each face 35 thereof, extending about the edges and projecting slightly beyond the same to protect

the board, with securing means passing through the material along different edges of the board and thence through the board and engaging the material on the opposite 40 face of the board.

2. A crate of plaster board or the like consisting of a plurality of said boards occupying a superposed relation, strips of suitable material placed about the edges of said 45 boards on each face thereof and projecting slightly beyond the edges of the boards, and securing means passing through the boards and engaging the strips on the opposite faces of the latter to fasten them together. 50

3. A crate of plaster board or the like consisting of a plurality of said boards occupying a superposed relation, strips of suitable material placed about the edges of said 55 boards on each face thereof and projecting slightly beyond the edges of the boards, the stripping on one face of the boards being of relatively soft material and the stripping on the opposite face thereof being of relatively hard material, and securing means such as 60 nails passing through the board from the relatively soft stripping and engaging in said relatively hard stripping, substantially as described.

In testimony whereof I have hereunto 65 signed my name in the presence of two subscribing witnesses.

JOHN H. NOLD
